UNITED STATES PATENT OFFICE.

FRÉDÉRIC AUGUSTE HENRI HARLÉ, OF PARIS, FRANCE, ASSIGNOR TO HARLÉ & CO., OF PARIS, FRANCE, A CORPORATION OF FRANCE.

SUBMARINE MINE.

1,298,937.

Specification of Letters Patent.

Patented Apr. 1, 1919.

Application filed June 11, 1914. Serial No. 844,500.

To all whom it may concern:

Be it known that I, FRÉDÉRIC AUGUSTE HENRI HARLÉ, of 26 avenue de Suffren, Paris, France, engineer, a citizen of the Republic of France, have invented new and useful Improvements in Submarine Mines, which improvements are fully set forth in the following specification.

This invention relates to a brake for such submarine mines as are provided with an anchor and an apparatus for regulating the depth of immersion of the mine.

In such mines while launching it is desirable that the rope connecting the anchor to the mine should be at a tension sufficient to keep it taut but not great enough to hold the mine below the surface while the rope is being unwound.

With this object it has already been proposed to provide the drum with automatic regulating brakes so as to correct as far as possible accidental variations in the strength of the brake and to avoid for instance oscillations in the level of the mine when thrown into the water. Most of such brakes however require regulation or adjustment just before use.

Apparatus constructed in accordance with this invention has not this effect.

According to this invention the brake is applied by the movement of a weight due to centrifugal force.

The invention is illustrated in the accompanying drawings in which Figure 1 is an end elevation of the brake mechanism and Fig. 2 is a partial section taken through the axis of the drum.

Fig. 3 is a view similar to Fig. 1 and showing a modification, and Fig. 4 is an assembly view with the anchor casing in section.

c is the drum upon which the mooring rope is wound, it is mounted upon a shaft *b* and provided with a cheek *a*. *d d* are spin-

45 dles (two for example) carried by the cheek *a* about which weighted arms *e* turn. The anchor *A* inclosing the foregoing parts is of any usual or desired construction.

In Fig. 1 the weights are shown in full lines resting against the shaft *b*.

When the drum *c* rotates centrifugal force tends to separate the weights *e* and cause them to take a position such as is shown in dotted lines.

Shoes *g* carried by the weighted arms rub

against the internal face of the fixed brake drum *h*.

In place of connecting the shoes directly to the weights *e*, a spring *i* and abutment *f* may be interposed as indicated in the drawing in which a spring *i* thrusts outward a plunger carrying the shoe *g*. The abutment *f* limiting the extension of the spring forces the shoe *g* to separate from the drum *h* when the weight *e* approaches the shaft.

The centrifugal movement of the weight may with a spring such as *i* be advantageously limited by a stop *k* to prevent the weights coming into contact with the drum *h*.

In the modification shown in Fig. 3 each shoe *g* is mounted not upon a plunger but on a lever *l* pivoted at *d* and the spring *i* acts directly upon the lever *l*.

As the speed of unwinding increases the weights *e* separating more under the effect of centrifugal force, will force the shoes *g* harder and harder against the drum *h*. If the unwinding slows from any accidental cause centrifugal force becomes less and the braking also becomes less. The unwinding is thus regulated.

When springs such as *i* are present the braking increases until the weights encounter the stops *k* and after this the braking force remains constant. If there are no abutments *k* the braking force will still continue to increase but slightly by reason of the direct friction of the masses against the drum *h*.

Having now particularly described and ascertained the nature of my said invention and in what manner the same is to be performed, I declare that what I claim is:

1. In a submarine mine, an anchor provided with a rope drum and a brake drum, in combination with a brake shoe, and means actuated by centrifugal action for increasing or diminishing the pressure of the brake shoe on the brake rim according to the speed of the rope drum.

2. In a submarine mine, an anchor provided with a rope drum and a brake drum, in combination with a pivoted weighted lever mounted on the rope drum and provided with a brake shoe, adapted to bear against the brake rim.

3. In a submarine mine, an anchor provided with a rope drum and a brake drum, in combination with a pivoted weighted

lever mounted on the rope drum and provided with a spring-pressed brake shoe, adapted to bear against the brake drum with pressure varying according to the speed of

5 the rope drum.

4. In a submarine mine, an anchor provided with a rope drum and a brake drum, in combination with a pivoted weighted lever mounted on the rope drum and provided with a spring-pressed brake shoe, adapted to bear against the brake drum, and a stop to limit the movement of the weighted lever.

10 5. In a submarine mine, an anchor provided with a rope drum and a brake drum, in combination with a brake shoe and a pivoted weighted lever, adapted to bear on the brake shoe with varying pressure according to the speed of the rope drum.

20 6. In a submarine mine, an anchor provided with a rope drum and a brake drum, in combination with a pivoted weighted lever, a brake shoe and a spring interposed between the brake shoe and the lever, an abutment limiting the extension of the

spring, and a stop for limiting the movement of the weighted lever, the brake shoe being pivoted on the same axis as the weighted lever.

7. In a submarine mine, an anchor provided with a rope-drum and a brake-drum, in combination with a pivoted weighted lever, a brake-shoe pivoted on the same axis as the weighted lever, a spring interposed between the brake-shoe and the lever, 30 a stop limiting the movement of the weighted lever and an arm extending from and forming part of the weighted lever, said arm being provided with a lip forming an abutment arranged in the path of the brake shoe, 35 to limit the movement of said shoe and the extension of the spring.

In testimony whereof I have signed this specification in the presence of two subscribing witnesses.

FRÉDÉRIC AUGUSTE HENRI HARLÉ.
